UNITED STATES PATENT OFFICE.

WILLIAM J. HAFSTROM, OF CHICAGO, ILLINOIS.

WATER-CRAFT.

1,372,749.

Specification of Letters Patent. Patented Mar. 29, 1921.

Application filed April 17, 1918. Serial No. 229,004.

To all whom it may concern:

Be it known that I, WILLIAM J. HAFSTROM, a citizen of the United States, and a resident of Chicago, in the county of Cook 5 and State of Illinois, have invented certain new and useful Improvements in Water-Craft, of which the following is a specification.

My invention relates to water craft, particularly to that class which when in motion is sustained partly by flotation on water and partly by the air.

The broad object of my invention is to produce a water craft which can be driven 15 at high speed by water engaging propulsion mechanism and then sustained in great part by suitable wings or vanes so that the craft can travel in a more horizontal line irrespective of the waves or broken water 20 surfaces.

More in detail, one important object of the invention is to provide propulsion mechanism in the form of hollow spiral propellers which in addition to acting as floats and 25 water engaging propellers, act also as air engaging propellers when raised above the water. Another feature of the invention is to provide vanes or wings suitably secured to and extending from the craft body for 30 sustaining a great part of the vehicle load when it is rapidly traveling in order that the craft, when in rapid progress, will hit only the high spots of the water, so to speak, suitable rudder mechanism being provided 35 for determining the direction of travel of the craft and for causing the desired elevation of the sustaining planes with reference to the horizontal.

The above and other features of my invention are clearly disclosed on the accompanying drawing in which—

Figure 1 is a plan view,

Fig. 2 is a side elevational view,

Fig. 3 is a rear elevational view,

Fig. 4 is a sectional view on plane 4—4,

Fig. 1, and

Fig. 5 is a sectional view on plane 5—5,

Fig. 1.

The supporting frame F of the craft is in 50 the form of a boat and constructed of sheet metal or other material and in such manner as to be strong and light. The prow 10 is shaped and curved so as to cut down the resistance when in the water. Extending 55 laterally from the front of the boat body are the brackets or arms 11 and 12 and at

the rear of the boat similar arms or brackets 13 and 14 extend laterally. These arms afford bearing support for the hollow spiral propeller structures P and P'. Each propeller structure comprises a hollow shaft section 15 surrounded by the hollow worm or thread 16, these parts being of sheet metal so that the propeller structures will be 60 strong and light and will serve as floats. The ends 17 and 18 of the propeller shafts are preferably conical so as to reduce the resistance when the craft is traveling 65 through the water or in the air. The ends of the shaft of the propeller P have bearing 70 in the ends of the arms 11 and 13, while the propeller P' has bearing support in the ends of the arms 12 and 14, the propellers being parallel with the craft body. The worm or 75 thread arrangement may be single or multiple and the pitch such that the craft can be given great speed when the propellers are rapidly rotated.

Extending from the crests of the propeller worms or threads and suitably spaced, are 80 the fins or vanes 19 whose pitch is the same as that of the threads. The arrangement of the vanes on each propeller is such that their engagement with the water will assist the threads or worms in rapidly propelling the 85 craft, and by their engagement with the air these vanes act together like the ordinary propellers of aeroplanes.

Describing now the driving mechanism for the propellers, a suitable engine E is 90 mounted in the craft body F, the engine shaft 20 being journaled at its outer end in the bearing structure or frame 21. Journaled in this frame structure and in the end wall 22 of the craft body are the transmission shafts 23 and 24 carrying outside of the wall 22 the intermeshing gears 25 and 26. The pinion 27 on the engine shaft meshes 95 with the pinion 28 on the transmission shaft 23 so that when the engine shaft is driven 100 the gears 25 and 26 will be rotated. The outer ends of the shafts 23 and 24 also support sprocket wheels 29 and 30 which are connected by chains 31 and 32 with the sprocket wheels 33 and 34 secured to the 105 propeller structures P and P' just within the arms 13 and 14, the rotation of the gears 25 and 26 being thus transmitted to the propellers. With the arrangement shown the 110 propellers are rotated in opposite directions, but the screws or worms are so arranged that the propellers will cause propulsion of

the craft in the same direction. By having the propellers rotate in opposite directions the craft will be balanced, that is, there will be no side pull or thrust when the propellers 5 are rotated.

Secured to and extending laterally from the sides of the craft body F are the planes or wings 35 and 36, these wings being rectangular and preferably parallel with the 10 propeller axes. Suitable anchor or tie rods 37 and 38 connect the outer corners of the wings with the ends of the craft body and keep the wings in proper alignment. At 15 their inner ends the wings are preferably curved to parallel the circumferences of the propellers, as clearly shown in Fig. 4.

R represents a rudder structure which comprises the horizontal steering plane 39 and the vertical steering plane 40 extending 20 downwardly from the center line of the horizontal plane. The rudder structure is pivoted at the apex of the V-frame 41 as indicated at p, which at the ends of its limbs is pivoted to the lugs 42 and 43 extending rearwardly from the arms 13 and 14, the frame 25 41 with the rudder structure pivoted thereto being therefore capable of being swung vertically and the rudder structure being capable of swinging horizontally at the 30 pivot p. At the front end of the craft body the operating mechanism O for the rudder structure is situated. The tubular shaft 44 is suitably journaled and carries a drum 45 for the cable ends 46 and 47 which extend 35 around guide pulleys 48 and 49 and fasten at their outer ends 50 and 51 to the rudder plane 39 so that turning of the hand wheel 52 secured to the shaft 44 will cause horizontal swing of the rudder around the pivot p. 40 Extending through the tubular shaft 44 is the shaft 53 which supports the drum 54 for the cable ends 55 and 56, the cable end 55 passing over the guide member 57 and being secured at its end 58 to the outer end of the 45 rudder structure at the top thereof. The cable end 56 travels around suitable guides 59 and 60 and is secured at 61 to the rear end of the rudder plane 40 a distance below the top thereof. With this arrangement turning 50 of the shaft 53 by the hand wheel 62 causes the rudder structure together with its supporting frame 41 to swing vertically around the center of the pivot connections 42 and 43.

55 When the craft is at rest its boat body F and the hollow propeller structures will support its weight, the dimensions being preferably such that the propeller structures will be only partly immersed in the water. 60 When the engine is operating and connected, the propeller structures will be rapidly rotated and the fins 19 coöoperating with the worms will cause the craft to acquire great speed through the water. The engagement 65 of the fins and worms with the water will

have a tendency to raise the craft with reference to the water in proportion as the speed increases, and thus the resistance is reduced. When the vehicle is under headway the wings or planes 35 and 36 will co-operate with the air to prevent sudden dropping of the craft where the water surface is broken or wavy. By adjusting the rudder structure the craft can be tilted so as to bring the sustaining planes at an angle with the horizontal, the planes then exerting raising effort on the craft and taking up the greater part of the load. The craft is thus practically carried bodily by the sustaining planes across the crests of the waves or 70 broken water surface and can travel in a straight line without having to follow the irregular water surface. Although the fins 75 19 of themselves are not able to propel the craft sufficiently to permit the sustaining planes to hold the craft entirely above the water, yet their engagement with the air adds greatly to their propulsion effect and 80 that of the worms in the water.

The craft is more or less self-controlling 90 during travel. If the tilted sustaining planes tend to carry the craft too far out of the water the engagement of the worms and fins for water propulsion will decrease and the speed of the craft retarded to permit it 95 to settle sufficiently in the water to increase the water propulsion area.

As the inner ends of the sustaining planes 100 curve around the propeller structures pockets are formed into and through which the propellers rapidly draw the air so that the sustaining effort of the planes is increased and steadied.

I thus provide a very simple yet highly 105 efficient water craft which can be propelled at great speed through and along the surface of a body of water and whose forward travel is along a straight line irrespective of waves or broken water surfaces.

I do not of course desire to be limited to the precise structure and arrangement 110 shown and described as changes and modifications are no doubt possible which would still come within the scope of the invention. I claim as follows:

1. A water craft comprising a body provided with planes extending laterally therefrom, a buoyant propeller mounted beneath said body and provided with a deep helical groove extending longitudinally thereof, and a plurality of blades mounted on said propeller intermediate said grooves.

2. A water craft comprising a body, a buoyant propeller mounted beneath said body and having a deep helical groove extending longitudinally thereof, a plurality of radially extending blades mounted on said propeller, and a horizontal rudder projecting from the rear of the body above the surface of the water.

3. A water craft comprising a body, buoyant propellers mounted beneath said body and having deep helical grooves extending longitudinally thereof, and blades arranged helically intermediate said grooves, a horizontal elevator mounted on said body, and means for elevating and depressing said elevator.
4. A water craft comprising a body, buoyant propellers mounted beneath said body
- 5 and having deep helical grooves extending longitudinally thereof, and blades arranged helically intermediate said grooves, and a combined horizontal elevator and vertical rudder mounted on said body, and elevator 15 and rudder controlling mechanism.

In witness whereof, I hereunto subscribe my name this 12th day of April, A. D. 1918.

WILLIAM J. HAFSTROM.
